(57) CLAIM

The ornamental design for a cosmetic container, as shown and described.

DESCRIPTION

FIG. 1 is a rear perspective view of a cosmetic container showing my new design;

FIG. 2 is a top view of the cosmetic container of FIG. 1;

FIG. 3 is a bottom view of the cosmetic container of FIG. 1;

FIG. 4 is a front view of the cosmetic container of FIG. 1;

FIG. 5 is a back view of the cosmetic container of FIG. 1;

FIG. 6 is a side view of the cosmetic container of FIG. 1;

FIG. 7 is another side view of the cosmetic container of FIG. 1;

FIG. 8 is an exploded perspective view of the top portion of the cosmetic container of FIG. 1; and,

FIG. 9 is an exploded perspective view of the cosmetic container of FIG. 1.

The top portion of the container is shown separately for convenience of illustration.

The broken line showing of the brush is included for the purpose of illustrating a portion of the article and forms no part of the claimed design.
